LIQUID PUMP

Charles H. Rickert, Wood River, Nebr.

Application December 24, 1934, Serial No. 759,107

2 Claims. (Cl. 103—103)

The invention aims to provide a simple and inexpensive, well-balanced, efficient and long-lived rotary pump designed primarily for irrigation purposes but not restricted to this field of use.

With the foregoing in view, the invention resides in the novel subject matter hereinafter described and claimed, description being accomplished by reference to the accompanying drawings.

Fig. 1 is a central longitudinal sectional view through a pump constructed in accordance with the invention.

Figs. 2 and 3 are horizontal sectional views on lines 2—2 and 3—3 of Fig. 1, respectively.

Fig. 4 is a perspective view of the lower section of the casing.

Fig. 5 is a perspective view of the rotor.

The pump casing C is provided with a cylindrical side wall 8, with a lower end wall 9 and with an upper end wall 10, said lower end wall 9 being provided with a liquid inlet 11 while said end wall 10 is formed with a liquid outlet 12, said inlet and outlet being centrally located and being suitably adapted for connection with pipes or couplings 13 and 14 respectively. The casing is preferably formed of upper and lower halves flanged and secured together by bolts 15 or connected with each other in some other adequate way.

Suitably mounted within the outlet 12 is a bearing 16 and I have shown spider legs 17 joining said bearing to said inlet. Within this bearing 16, a rotor shaft 18 is so mounted that it may freely rotate but is held against endwise movement. The rotor comprises the shaft 18, a disk 19 centrally secured to the lower end of said shaft, and a plurality of spirally directed vanes 20 secured to the lower side of said disk. The disk 19 is disposed about midway between the end walls 9 and 10 and its peripheral edge is spaced from the casing side wall 8. The vanes 20 extend to the edge of the disk 19 from the periphery of the liquid inlet 11 and the curvature of these vanes radially delivers the liquid from the rotor and of course also moves the liquid circumferentially.

Helically pitched vanes 21 are secured to the cylindrical side wall 8 of the casing between the periphery of the rotor and said side wall, said vanes 21 being so pitched as to elevate the liquid into the space between the disk 19 and the end wall 10. Fixedly mounted in this space, preferably by securing them to the end wall 10 and the

side wall 8, are spirally pitched vanes 22 which direct the liquid to the outlet 12.

I preferably provide a web 23 extending diametrically across the inlet 11 in a plane extending longitudinally of the axis of said inlet, for the purpose of preventing whirling of the liquid during its passage through said inlet, thus allowing the spirally pitched vanes 20 to more effectively act upon the liquid to centrifugally deliver it.

The shaft 18 may, of course, be driven in any suitable way and when this shaft is rotated, the liquid is centrifugally delivered by the rotor vanes 20 and is circumferentially moved also by these vanes. The circumferentially moving, radially delivered liquid is elevated by the helically directed vanes 21 and this liquid is directed to the outlet 12 by the spiral vanes 22. The pump is well balanced, requires little power for its operation, is highly efficient, and long-lived.

While the details disclosed may be followed if desired, variations may of course be made within the scope of the invention as claimed.

I claim:

1. A water pump comprising a cylindrical casing whose length is less than its diameter, said casing having one flat end wall provided with a central relatively small inlet spanned by a flat web in a plane unidirectional with the casing axis, said casing having a second flat end wall provided with a central outlet of substantially the same diameter as said inlet, a bearing secured centrally in said outlet, a rotor in said casing co-axial with the cylindrical side wall of said casing, said rotor comprising a central shaft rotatably and non-slidably mounted in said bearing, a flat imperforate disk secured at its center to said shaft and situated substantially midway between said end walls, the peripheral edge of said disk being spaced from said casing side wall, and spirally directed water-moving vanes secured to the side of said disk toward said one end wall, said vanes extending from said disk substantially to said one end wall and extending from said inlet to said edge of said disk, helically directed water-moving vanes secured to said casing side wall around said rotor and extending from said one end wall substantially to the plane of said disk, and spirally directed water-moving vanes situated between said disk and said second end wall, these vanes being secured to said second end wall and to said side wall, extending from said second end wall toward said disk and extending from said side wall to said outlet.

2. A water pump comprising a cylindrical casing whose length is less than its diameter, said casing having one end wall provided with a central relatively small inlet, said casing having a second end wall provided with a central outlet of substantially the same diameter as said inlet, a bearing secured centrally in said outlet, a rotor in said casing coaxial with the cylindrical side wall of said casing, said rotor comprising a central shaft rotatably and non-slidably mounted in said bearing, an imperforate disk secured at its center to said shaft and situated substantially midway between said end walls, the peripheral edge of said disk being spaced from said casing side wall, and spirally directed water-moving vanes secured to the side of said disk toward said one end wall, said vanes extending from said disk substantially to said one end wall and extending from said inlet to said edge of said disk, helically directed water-moving vanes secured to said casing side wall around said rotor and extending from said one end wall substantially to the plane of said disk, and spirally directed water-moving vanes situated between said disk and said second end wall, these vanes being secured to said second end wall and to said side wall, extending from said second end wall toward said disk and extending from said side wall to said outlet. 5 10 15
